SHOE FINISHING MACHINE

Charles E. Thibaudeau, Ivry-sur-Seine, France, assignor to United Shoe Machinery Corporation, Boston, Mass., a corporation of New Jersey

Application July 8, 1931, Serial No. 549,387, and in France July 30, 1930

19 Claims. (Cl. 12—78)

This invention relates to shoe finishing machines and is herein illustrated as embodied in a device for burnishing the sole edges of shoes.

It is well known to those skilled in the art of finishing shoes that the sole edge burnishing operation can be performed best by the use of a machine having an oscillating tool. While individual machines of this type are in common use in shoe factories, their relatively great expense prohibits their general use in shoe repairing establishments where rotary tools attached to finishing shafts, carrying also a number of other tools for polishing, padding and scouring, etc., are usually employed for burnishing sole edges.

Edge burnishing machines of the type to which this invention relates, as heretofore commonly constructed, comprise a tool holder adapted to be oscillated, a rotating drive shaft, and a tool holder driving means for causing the tool holder to be oscillated so long as the shaft is rotated. Since, in the use of finishing machines comprising a plurality of tools for performing different operations successively, only one of them is used at once, each tool is used during only a small part of the time during which the machine is in operation. It follows that an oscillating edge finishing tool, if it continues to be operated idly in such a machine, would be subjected to considerable unnecessary wear when any of the other finishing tools in the machine were in use.

One object of the invention, therefore, is to make it possible for an operator of a machine of the type above described operatively to connect an oscillating edge setting machine attachment with or disconnect it from a finishing shaft as he wishes to use it or not. To this end, one feature of the invention consists in the provision in a finishing machine of the combination with a tool holder, and driving means for oscillating the tool holder mounted for movement into and out of driving engagement therewith, of means for operatively connecting the tool holder driving means with or disconnecting it from the tool holder. In the illustrated machine, the tool holder driving means is constituted by an arm or lever arranged to slide on the holder and also to engage a cam on the drive shaft, which causes the arm to be oscillated when the shaft is rotated. An operative connection between the tool holder and arm is afforded by complementary clutch faces on the holder and arm which are normally urged apart, but which may be held together by means of a control element movable in opposite directions

and constructed and arranged to hold the clutch faces in driving engagement when in one extreme position and to allow the clutch faces to be separated as it is moved to its other extreme position. Still another feature of the invention resides in the provision of means for releasably securing said controlling member in either of its extreme positions whereby the driving engagement between the holder and the lever is either maintained or prevented.

In order to insure the proper re-engagement of the above-mentioned clutch faces, the illustrated embodiment of the invention also comprises means forming another feature thereof for limiting the movement of the tool holder in excess of its normal oscillatory movement. As herein shown, the rotative movement of the holder with respect to the frame, when disconnected from its driving means, is limited by means of adjustable stops on one arranged to engage shoulders on the other.

These and other objects and features of the invention will become apparent from a consideration of the following description and drawings, in which—

Fig. 1 is a plan view of one embodiment of the invention;

Fig. 2 is a sectional elevation taken along the line II—II in Fig. 1; and

Fig. 3 is a sectional elevation taken along the line III—III in Fig. 1.

The invention is illustrated herein as embodied in a finishing machine of a type best known as a "finishing shaft," comprising a rotatable tool shaft 10 adapted for carrying a plurality of padding, burnishing and scouring tools and the like rotatably supported at various points along it by a plurality of ball bearings 12 which are housed in retainers 14. Each of the retainers is mounted to swivel on studs 16 which are threaded into the ends of U-shaped hangers 18 which are usually made integral with frame elements (not shown) adapted to support the shaft from the floor or from the wall.

The frame 20 for the device in which the present invention is illustrated as embodied is secured to one of the retainers 14 by means of bolts 22 and rotatably supports in the upper portion thereof a shank 24 on a tool holder 26 and also encloses a tool-holder driving lever or arm 28. The lever 28 is mounted to slide and to rotate on the shank 24 and is continuously oscillated, so long as the shaft 10 is rotated, by means of a cam 30 which rotates with the shaft 10.

In order to relieve the cam 30 from resisting any

110

axial thrust of the shaft 10, which preferably is absorbed by the bearings 12, the cam is loosely mounted on the shaft 10 and arranged to bear against a shoulder 32 of the frame 20 and a flange 34 secured to the outer side of the frame 20 opposite the shoulder 32. The cam 30 is thus prevented from having any substantial lateral movement in the frame 20. The cam 30 is caused to rotate with the shaft by means of connections 10 comprising a collar 36 secured to the shaft by means of set screws 38, and having lugs 40 both extending from its inner radial face and entering complementary recesses in a rim 42 of the cam 30. A fibrous washer 44 retained in a groove 15 in the flange 34 and adapted to bear on the peripheral face of the rim 42 prevents the entry of any foreign matter into the vicinity of the operating mechanism. A stud 46 fixed in the lower end of the lever 28 and carrying a cam roll 48 20 arranged for engagement within the track in the cam 30 constitutes the driving connection between the cam and the lever.

The finishing tool 50 is of conventional type and is secured by a collet 52, operated by a hand 25 lever 54, in a spring chuck 56 on the lower end of a sleeve 58 slidably received in the head of the tool holder 26. Upward pressure of a shoe against the tool is yieldingly resisted by a rod 60 bearing at one end on a seat in the sleeve 58 and 30 being urged downwardly by means of a spring 62. The above construction is more fully described in copending application Serial No. 551, 466 filed on July 17, 1931, in the names of Keall and Jones.

35 While, as above pointed out, the lever 28 is constantly oscillated so long as the shaft 10 is rotated, it is not subjected to any substantial load unless it is operatively connected with the tool of the shank 24. It thus appears that by providing 40 a mechanism by means of which an operator can disconnect the lever 28 from the tool holder shank 24 at will, unnecessary wear in the machine which would result from the oscillation of the entire operating mechanism although no 45 work is being treated is eliminated.

The above end is attained in the illustrated construction by providing cooperative clutch faces on the lever 28 and the shank 24 and mechanism for holding them in or out of driving engagement. As herein illustrated, the clutch faces comprise shoulders on a tooth 64 radially disposed on a flange 66 effectually integral with the shank 24 and also at the sides of a recess 68, cut in the face of the lever 28 adjacent to the flange 66. 50 While it is desired to oscillate the tool 50, the shoulders on the tooth 64 are held in abutting relation with the sides of the recess 68 by means later to be described; but the cooperating faces of the tooth and recess are normally urged apart by means of a spring 70 which bears at one end 55 against a washer 72 abutting a ball 74 which is seated in a depression in the end of the shank 24. The opposite end of the spring 70 engages the outer end of a hub 76 on the lever 28 and extending away from its clutch face. The hub, as indicated in Fig. 3, is recessed and encloses the spring 70. The hub 76 is not only supported internally by means of the shank 24 but also externally in a bearing member 78 which is secured to the frame 60 70 by means of screws 80.

The means above referred to for holding the lever 28 and the tool holder shank 24 in driving engagement comprises a control element 82 arranged to slide and to rotate in the bearing element 78 and having adjustably fixed to its outer

end a handle 84. Rotation of the control element 82 causes also an axial movement thereof on account of a helical groove 86 in the control element within which is engaged the end of a stud 88 which is fixed in the bearing element 78. An 80 adjustable connection between the control element 82 and the hub 76 is afforded by a rod 90 threaded centrally in the control element 82 and arranged to abut a ball 92 seated in a recess in the end of the hub 76. A lock nut 94 on the outer 85 end of the rod 90 may be tightened against the handle 84 to hold the rod in any desired position of adjustment.

It is now apparent that when the control element 82 is turned by means of the handle 84 so as 90 to screw the control element outwardly of the bearing element 78, the spring 70 is allowed to move the lever 28 a corresponding amount in the same direction, eliminating the driving engagement between lever 28 and the shank 24. An 95 opposite movement of the control element, on the other hand, causes relative approach of the clutch faces on the lever 28 and the shank 24 and sufficient continued rotation of the control element in this direction will cause the tooth 64 to be held 100 firmly in engagement with the sides of the recess 68.

The control element 82 is arranged to be locked both in this position and at the other extreme of its travel by means of a plunger 96 (Fig. 1) slidably received in the bearing element 78 and having a pointed end arranged to be received within either of two recesses in the inner side face of the handle 84. The plunger 96 is held yieldingly in engagement with the handle 84 by means of a 110 spring 98 bearing on the inner end of the plunger 96 and the base of the recess in which the plunger is received.

In order to insure the proper re-engagement of the tooth 64 against the sides of the recess 68 in 115 the lever 28 when it is desired to establish the driving connection between the lever and the shank 24, the invention also provides means for limiting the movement of the tool holder in excess of its normal oscillatory movement. As herein 120 shown, this means comprises stop screws 100 threaded into a side of the bearing element 78 in the vicinity of the flange 66 which, as described above, is fixed to the shank 24. The inner ends of the stop screws 100 are arranged to 125 enter notches in the flange 66 and to engage faces 102 of the notches to limit the rotative movement of the shank 24 when it is disconnected from the lever 28. The stop screws 100 may be secured in any desired position of adjustment by means of 130 lock nuts 104.

To facilitate the presentation of a shoe to the burnishing tool 50 the illustrated machine is provided with a hand grip 106 below and behind the tool and secured in a boss 108 at the base of the 135 frame 20 by means of a set screw 110.

In view of the foregoing the mode of operation of the machine is thought to be apparent but will now be briefly summarized. Assuming that the drive shaft 10 is rotating the tool holder driving 140 lever 28 is continuously oscillated by the cam 30 through the roll 48 on the lever which extends into the cam track. While the shank 24 has no substantial axial movement but only oscillates, 145 the driving lever 28 is arranged to slide axially on the shank 24 as well as to rotate about it so that a driving connection between the lever 28 and the shank 24 may be readily established or eliminated. Such axial movement of the lever 28 is 150

5 relatively limited and is insufficient to move the cam roll 48 out of the track in the cam 30. The cooperating clutch faces on the flange 66 and the lever 28 tend to separate on account of the action of the spring 70 the ends of which abut the adjacent ends of the shank 24 and the hub 26 of the lever 28; but the clutch faces on the flange 66 and lever 28 are either held in engagement or allowed to separate under the effect of the spring 10 by a corresponding movement of the control element 82 which, when turned, moves axially either in or out of the bearing element 78.

Having thus described my invention, what I claim as new and desire to secure by Letters Patent of the United States is:

1. In a finishing machine, a tool holder, a shaft, means for driving said tool holder mounted for movement into and out of driving engagement therewith, means on said shaft for oscillating said tool-holder-driving means as the shaft is rotated, and means for operatively connecting said tool-holder-driving means with or disconnecting it from the tool holder.

2. In a finishing machine, a tool holder, a drive shaft, means thereon for operating said tool holder, driving means engaging said last-mentioned means mounted for movement into and out of driving engagement with said tool holder, and means for holding said tool holder and said driving means in or out of driving engagement with each other whereby the tool holder is caused to oscillate or not.

3. In a finishing machine, an oscillating tool holder, a drive shaft having a cam, means connecting said holder and cam comprising an arm engaging said cam and arranged to slide on said holder into and out of driving engagement therewith, and means for moving said arm into driving engagement with the tool holder.

4. In a finishing machine, a rotatably mounted tool holder, a rotating drive shaft, an arm for operating said holder mounted for axial movement and to rotate coaxially with respect to said tool holder, means connecting said shaft and said arm for causing the arm to be continuously oscillated, and means for moving said arm axially with respect to said tool holder thereby to establish an operative connection therebetween.

5. In a finishing machine, a drive shaft, a tool holder, an operating lever therefor constructed and arranged for clutching engagement with said holder, means on said drive shaft for causing said lever to oscillate, means tending normally to hold said holder and lever out of clutching engagement with each other, and means for maintaining driving engagement between said holder and said lever thereby to cause the tool holder to oscillate.

6. In a finishing machine, a tool holder, a frame rotatably supporting the holder, and means for limiting the rotative movement of the holder in the frame comprising adjustable stops on one arranged to engage shoulders on the other.

7. In a finishing machine, a tool holder having a shank, a frame rotatably supporting the holder shank, said shank being notched to form opposed shoulders, and stops mounted in said frame adjustably to limit rotative movement of said shank and frame.

8. In a finishing machine, a tool holder, a rotating drive shaft, connections between said tool holder and the drive shaft for oscillating the tool holder constructed and arranged for movement into and out of operative engagement with the tool holder, and means for adjustably

limiting movement of the tool holder when said connections are disengaged therefrom.

9. In a finishing machine, a tool holder, a rotating drive shaft, connections between said holder and said drive shaft for oscillating the tool holder constructed and arranged for movement into and out of operative engagement with the tool holder, and adjustable stops for limiting movement of the tool holder when said connections are disengaged therefrom.

10. In a finishing machine, a drive shaft, a tool holder having a clutch face, a lever for operating said holder having a clutch face complementary to that on said holder, means on said drive shaft for causing the lever to oscillate when the shaft is rotated, and means for alternatively maintaining the clutch faces on said holder and lever in driving engagement with each other and for disconnecting them.

11. In a finishing machine, a drive shaft, a tool holder having a clutch face, a lever having a clutch face complementary to that on the tool holder and mounted for movement on said tool holder toward and away from said holder, means on said shaft for causing the lever to be oscillated when the shaft is rotated, means for urging said clutch faces apart, and a control element constructed and arranged to move said lever into driving engagement with said tool holder and to allow separation of the said clutch faces.

12. In a finishing machine, a drive shaft, a tool holder having a clutch face, a lever for operating said tool holder having a clutch face complementary to that on said holder, means on said shaft for causing the said lever to be oscillated when the shaft is rotated, and a rotatable control element constructed and arranged to move said lever to bring its clutch face into engagement with that on the tool holder.

13. In a finishing machine, a drive shaft, a tool holder having a clutch face, a lever for operating said holder having a clutch face complementary to that on said holder, means on said shaft for causing the said lever to be oscillated when the shaft is rotated, and a rotatable control element constructed and arranged when turned to move said lever axially to bring its clutch face into engagement with that on the tool holder.

14. In a finishing machine, a drive shaft, a tool holder having a clutch face, a lever for operating said tool holder and having a clutch face adapted for engagement with the clutch face on said holder, means between said holder and said lever tending to separate their clutch faces, means on said shaft for causing said lever to be oscillated when the shaft is rotated, a rotatable control element constructed and arranged when moved to bring the clutch face of the lever into engagement with that on said tool holder, and means for releasably securing said control element whereby said clutch faces are held in operative relation.

15. In a finishing machine having a frame rotatably supporting a tool holder, a clutch face on said tool holder, a lever rotatably supported by said tool holder and in said frame, complementary clutch faces on said lever and said tool holder, a drive shaft, means on said drive shaft for oscillating said lever when the shaft is rotated, a control element adapted for engagement with said lever and rotatably mounted in said frame, a spiral shoulder on said control element, and an abutment in said frame arranged to engage

gage said shoulder whereby said lever is moved axially when said control element is rotated.

16. In a finishing machine, a tool holder, a rotating drive shaft, an arm connecting said tool holder and shaft mounted for sliding movement on said tool holder, means on said shaft for oscillating said arm, and means for moving said arm into or out of driving engagement with said tool holder whereby the tool holder is caused to oscillate or not.

17. In a finishing machine, a tool holder, a drive shaft, means connecting said holder and shaft for causing the holder to be oscillated, yielding means for urging said last-mentioned

means normally out of operative relation with respect to said holder, and means for moving said means connecting said holder and shaft into operative relation with respect to said holder whereby the tool holder is oscillated when the shaft is rotated.

18. In a finishing machine having a frame rotatably supporting a tool holder, a lever mounted on said tool holder rotatably supported on said

frame, cooperating clutch faces on said holder and lever, a drive shaft, means on said drive shaft for oscillating said lever when the shaft is rotated, a control element movable in opposite directions to cause said clutch faces to be held alternatively in or out of driving engagement, and means for releasably securing said control element in either of its extreme positions.

19. In a finishing machine having a frame rotatably supporting a tool holder, a lever mounted on said tool holder rotatably supported on said

frame, cooperating clutch faces on said holder and lever, a drive shaft, means on said drive shaft for oscillating said lever when the shaft is rotated, a control element movable in opposite directions to cause said clutch faces to be held alternatively in or out of driving engagement with each other, and a spring plunger adapted for engagement with seats on said control element

for releasably securing it in either of its extreme positions.
